Wm. M. Bell.

INVENTOR
James H. Harrett,
By
John Edward,
ATTORNEY.

UNITED STATES PATENT OFFICE.

JAMES H. HARRETT, OF NUTLEY, NEW JERSEY.

SPINDLE.

Application filed November 14, 1922. Serial No. 600,850.

To all whom it may concern:

Be it known that I, JAMES H. HARRETT, a citizen of the United States, residing at Nutley, in the county of Essex and State 5 of New Jersey, have invented certain new and useful Improvements in Spindles, of which the following is a specification.

The object of this invention is to provide a spindle which will be adapted to grip 10 the bore of the member, as a cop tube, arranged thereon and which will also be adapted to receive cop tube or the like members varying widely in diameter and yet hold them securely in a position of perfect alinement with respect to the axis of 15 the spindle. Spindles having springs to grip the bores of cop tubes and the like, such springs usually being in the form of arched or bowed longitudinal wires, are 20 known, but such spindles have heretofore been designed and adapted to receive cop tubes whose bores varied at most only a very little in diameter: if a cop tube having a bore of appreciably greater diameter 25 than that of the spindle proper were used on the spindle then the tube would not be held securely in axial alinement with the spindle, because the spring alone would not serve to hold it in such alinement. According 30 to this invention, given a spindle of the type which is equipped with spring means to grip the bore of a cop tube or the like, I provide the spindle with a conical enlargement which tapers toward the spring 35 means and is adapted to receive the contact of the butts or cop tubes varying very appreciably in diameter.

In the drawing,

Fig. 1 is a side elevation of the spindle 40 embodying my invention, parts thereof appearing in section;

Fig. 2 is a sectional view on the line 2—2, Fig. 1, on a larger scale; and

Fig. 3 is a side elevation of the spindle 45 and the cop tube thereon, the latter being shown partly in section.

a designates the spindle proper. Near its free end the spindle has holes formed therein at right angles to its axis and to 50 each other and through which are passed spring wires *b* which are bent downwardly and then have their free ends lying in grooves *c* formed in the spindle proper, the

wires being bowed outwardly between their free ends and the points where they pass 55 through the mentioned holes in the spindle. This construction is well known in the art.

Formed or in some suitable way secured rigidly on the spindle proper is an enlargement *d* which is tapered towards the free 60 end of the spindle, that is toward the spring means *b*. In the present case the enlargement is a separate collar fitted over the spindle proper and embracing the portions of the slots *c* in which the ends of the 65 springs *b* are arranged, so the collar is slotted at *d'* to accommodate the springs. By this arrangement the springs are securely held at their ends which engage the 70 collar, they are kept truly radial and the whole structure is cheaply made and may be readily assembled.

In view of the foregoing it will be seen that cop tubes *e* varying widely in diameter 75 may be used with the improved spindle. That is, cop tubes varying in diameter to the extent represented by the difference between the diameters at the smaller and larger ends of the enlargement *d* may be 80 fitted to the spindle and in each case if the butt of the tube is made to contact squarely against the conical surface of the enlargement the latter and the springs will coact to hold the tube, whatever its diameter, in perfect axial alinement with the 85 spindle. This would not be possible with the ordinary spindle provided with springs as *b* because, while such a spindle might have been constructed to at least receive 90 cop tubes varying in diameter, it would obviously not hold the larger tubes in true axial alinement with the spindle because the spindle proper would in such case be 95 relatively too small to resist appreciably skewing of the cop tube thereon.

In short, when the tube is slipped on the spindle embodying my invention, whatever its diameter it undergoes centering in two approximately separated zones thereof— 100 one at its base, where it is jammed against the cone, and the other where it is subject to the radial pressure of the springs.

Having thus fully described my invention, what I claim as new and desire to secure by Letters Patent is:—

A spindle including a spindle proper, a

collar arranged thereon and adapted to form a stop for a cap tube slipped onto the spindle and having equidistant radial and longitudinal slots formed in the end thereof adjoining the free end of the spindle, and outwardly bent spring devices each secured to the spindle at a point removed from the collar and having free ends arranged with-in the collar and confined against radial movement and being engaged in the slots. ¹⁰ In testimony whereof I affix my signature.

JAMES H. HARNETT.
